CLAIM

The ornamental design for a mobile patient bed controller, as shown and described.

DESCRIPTION

FIG. 1 is a perspective view of a mobile patient bed controller of the present application;

FIG. 2 is a front view of the mobile patient bed controller;

FIG. 3 is a rear view of the mobile patient bed controller;

FIG. 4 is a right side view of the mobile patient bed controller;

FIG. 5 is a left side view of the mobile patient bed controller;

FIG. 6 is a top view of the mobile patient bed controller; and,

FIG. 7 is a bottom view of the mobile patient bed controller.

In the drawings, the broken lines are for the purpose of illustrating environment only and form no part of the claimed design.

1 Claim, 4 Drawing Sheets
